UNITED STATES PATENT OFFICE

KARL LEHMANN, OF ESSEN, GERMANY

PROCESS OF DRESSING COAL

Application filed July 19, 1930, Serial No. 469,239, and in Germany July 31, 1929.

The general purpose of the process of dressing coal, as heretofore practised, is to separate shale and like impurities from the coal, which is done by a wet or a dry process, 5 and to grade the coal according to size, crushing apparatus being sometimes used as aids for this purpose. When graded according to size, by these methods, the coal in the various grades is still in the main of approximately uniform average petrographic and chemical composition.

The object of my invention is to effect the dressing with grading of the coal according to its petrographic constituents.

Modern research has shown that coal, previously regarded as a substantially homogeneous substance, consists in fact of three constituent substantially different from each other, namely:—(1) Vitrite, (2) Durite, (3) Fusite.

In addition to purely physical differences the chemical compositions of these constituents differ substantially from each other, and the same are, accordingly, not all equally well adapted for the same uses. Fusite, for example, is best adapted for powdered fuel furnaces, and vitrite is best adapted for coking, fusite and durite being inferior coking coals. Durite is best adapted for gasification, production of oil and various chemical processes.

The differences in regard to physical properties have already been recognized heretofore, and suggestions have been made for utilizing the same for grading the coal. It has in fact been suggested in print, that breaking up the coal to particular sizes may result in separating it according to these inherent physical differences, but no tests appear to have been made to ascertain whether this method would produce useful results. I have found that ordinary methods of disintegrating, as employed in connection with the dressing of coal, are not effective for separating the petrographic constituents, whereas such separation can be effected by subjecting the coal to elastic percussion or to resilient disintegrating action. Some known kinds of granulating apparatus subject the material treated to elastic percussion, but these have

not been used for coal, except possibly for the particular purpose of reducing the coal uniformly to granules of a particular size.

Elastic percussion or the resilient disintegrating action applied in accordance with my invention reduces the coal to granules or lumps of different sizes, the smallest consisting of fusite, which is more or less friable, and the intermediate size being the brittle vitrite. The hard, resilient durite resists the blows longest, and furnishes the largest pieces. After the elastic percussion the three petrographic constituents can easily be separated by screening or by other suitable means.

The elastic percussion may be applied by subjecting the coal to elastic blows or taps, or by flinging or beating it, as in a mill with beaters. For example, the coal may be placed in a rotating sifting drum in which there is a shaft, rotating in the same or in the opposite direction, with elastic beater bars fixed thereto. In many cases it may be necessary to repeat the elastic percussive treatment, in order thoroughly to separate the intimately associated petrographic constituents of the raw coal. Separation of impurities may precede this treatment, but it may be convenient to first effect a preliminary separation of the petrographic constituents, then clean the coal, and finally complete the separation of the petrographic constituents. In the case of clean coal the elastic percussive treatment is, of course, sufficient for all purposes. A particular advantage of the process is that it can be performed wholly dry.

In regard to the separation of the fusite, it is found that from the economic point of view suction gives better results than screening or sifting. Tests carried out, accompanied by petrographic analysis, have shown that the elastic percussive treatment accompanied by fairly powerful suction throughout the appliance results in almost complete separation of the fusite, without screening. Tests have also shown that a vitrite content up to 85% and a durite content up to 80% may be obtained.

One method of carrying the invention into

effect and two forms of mills are shown in the annexed drawings, in which:—

Figure 1 is a flow sheet illustrating the method.

Figure 2 is a vertical sectional view of a mill, and

Figure 3 is a vertical section of a modified form of mill.

The coal is fed from a hopper *a* to a classifying drum or vibrating screen *b*, which separates it into granules of three sizes 1, 2 and 3. The coarsest coal is treated on cleaning bands *c* or by means of other suitable appliances for separation of the coarser impurities. A breaker *d* is provided for elastic treatment whereby preliminary separation according to petrographic constitution is effected, the separation being effected so that the vitrite remains in the most finely divided coal, the vitrite in the middlings, and the durite in the coarse coal. For this purpose a disintegrator may, for example, be used, the coal of sizes 1 and 2 being fed to the same. The coal discharged from the mill, together with the coal 3 from the screen *b*, passes to the screen *e*, which may be a vibrating screen and separates the coal according to three sizes 4, 5 and 6, which are delivered separately to three cleaning tables *g* with suction hoods, of a known type, for separating shale, but the most finely divided coal first passes through a pneumatic sifter *f*. The most finely divided clean coal 7 taken from the cleaning tables consists almost exclusively of vitrite, and is conveyed away for use. The two coarser fractions 8 and 9 are fed to mills *h* with elastic beaters, which complete the separation according to petrographic constitution. The mills may, for example, consist of screening drums in which there are shafts with elastic beaters, rotating in the same direction as the drums or in the opposite direction, at appropriate speeds, the fineness of the screens depending on the petrographic structure of the coal. The beaters may be arms elastically connected to the shafts. By striking the coal they separate the vitrite from the durite, the former being discharged through the screen.

The fine coal dust separated by the suction appliances at the various stages, particularly the cleaning tables and mills, is practically free from durite, and consists mainly of fusite, with some vitrite. It is deposited and collected by means of cyclone appliances *i*, or in any other convenient way. Shale and other coarser impurities coming from the cleaning bands *c* and principally from the cleaning tables *g* are led away on line *B*.

Substantially complete separation of the raw coal into its petrographic constituents is thus effected, but in regard to detail the mode of procedure may be varied in many

respects without departing from the principle of the invention.

It may be mentioned that the process can be applied with great advantage to coal loaded with sulphur, as it is found that the elastic percussive treatment causes the sulphur to become concentrated mainly in one of the fractions, so that separation thereof by appropriate means is facilitated.

Two forms of mills have been illustrated in Figures 2 and 3 in which Figure 2 consists essentially of a sieve drum 1 which surrounds a percussion device consisting of a plurality of elastic beater bars 3. These bars are pivoted as pendulums and are secured to the shaft 2 of the mill by means of the circular disks 5. The drum 3 receives its rotation from the driving pulley 6 and the shaft 2 receives its rotation from the driving pulley 7. The material to be treated is placed in the mill through the entry tube 8 and enters the interior of the drum 1 at the right end of the drum. The material after being treated leaves the drum at the left end by means of the openings 9. In this manner the coal which is to be disintegrated will be repeatedly struck by the bars 3 and the coal will thus be divided into its three constituents in that the harder material, durite, which will be larger kernels, will be forced against the sides of the drum and eventually will fall into the container 10. The other particles vitrite and fusite which will be in the form of smaller kernels will fall through the sieve and will eventually be deposited into the container 11. The fusite is separated from the vitrite by suction so that eventually only the vitrite will be contained in the container 11. The entire mill is disclosed in a dust-proof casing 12.

In Figure 3 a modified form of mill is shown which consists of an outer casing or mantle 13 which surrounds the inner mantle 14 arranged in the form of steps. Centrally of the mill there is arranged a shaft 15 which contains the beater arms 16 having at their ends the beater 17. From the top to the bottom the beater arms progress in length as clearly shown on the drawings. In the mantle 14 there are arranged sieves 18 which are arranged at an angle. The angular surfaces 25 form baffle surfaces. The coal is placed into the mill through the inlet 19 and it is treated by the beaters 17 during its descent through the mill. The finely divided vitrite and fusite will be forced through the sieves 18 and they will eventually fall through the outlet 21. However, the extremely fine fusite may be forced by suction through the outlet opening 20 at the top so that in that manner the material falling through the outlet 21 is merely vitrite. The sieves 18 decrease in size from the top to the bottom but the durite which remains in the mill will eventually fall through the bottom into the trough 22, 330

through the vibration sieve 23 and the very fine fusite remaining will be forced by suction out through the pipe 24.

I claim:—

- 5 1. A process of dressing coal, comprising subjecting the coal to elastic percussion, whereby the fusite, durite and vitrite constituents are respectively broken up into granules of different sizes, and separating the granules of different sizes by screening.
- 10 2. A process of dressing coal, comprising subjecting the coal to elastic percussion, whereby the fusite, durite and vitrite constituents are respectively broken up into granules of different sizes, separating the granules of durite and vitrite by screening, and removing the fusite by suction.
- 15 3. A process of dressing coal, comprising subjecting the coal to repeated elastic percussive treatments, whereby the fusite, durite and vitrite constituents are respectively broken up into granules of different sizes, separating the granules of durite and vitrite by screening, and removing the fusite by suction.
- 20 4. A process of dressing coal, comprising first subjecting the coal to elastic percussive treatment for preliminary division thereof into its fusite, durite and vitrite constituents, then separating the impurities from the coal, subjecting it to further plastic percussive treatment, whereby the said constituents are respectively broken up into granules of different sizes, and finally separating said
- 25 5. A process of dressing coal, comprising subjecting the coal to repeated elastic percussive treatments, whereby the fusite, durite and vitrite constituents are respectively broken up into granules of different sizes, separating the granules of durite and vitrite by screening; and subjecting the coal to suction at the successive stages of treatment, whereby the fusite is separated.
- 30 6. A process of grading coal by disintegration thereof and separation of the several macroscopic banded constituents, comprising in subjecting the coal to resilient disintegrating action whereby the constituents are broken up into granules of different sizes and separating the granules of different sizes.

In testimony whereof, I affix my signature.
KARL LEHMANN.
